UNITED STATES PATENT OFFICE.

GEORGE F. KEARNEY, OF GORHAM, NEW YORK.

DESIGN FOR A SET OF PLAYING-CARDS.

45,670.

Specification for Design.

Patented Apr. 28, 1914.

Application filed January 30, 1914. Serial No. 815,553. Term of patent 14 years.

To all whom it may concern:

Be it known that I, GEORGE F. KEARNEY, a citizen of the United States, residing at Gorham, in the county of Ontario and State of New York, have invented a new, original, and ornamental Design for a set of Playing-Cards, of which the following is a specification, reference being had to the accompanying drawing, forming part thereof.

Figure 1 is a face view of one of the cards of the set showing two diamond pips and two spade pips; Fig. 2 is a similar view of

another card displaying two diamond pips and two club pips; Fig. 3 is a similar view showing two club pips and two hearts; and Fig. 4 is a like view showing two hearts and two spades.

I claim:

The ornamental design for a set of playing cards, as shown.

GEORGE F. KEARNEY.
